UNITED STATES PATENT OFFICE.

HENRY J. GOLDMAN, OF TROY, NEW YORK.

DESIGN FOR A HORSESHOE.

SPECIFICATION forming part of Design No. 18,980, dated April 2, 1889.

Application filed February 5, 1889. Serial No. 298,770. Term of patent 14 years.

To all whom it may concern:

Be it known that I, HENRY J. GOLDMAN, a citizen of the United States, residing at the city of Troy, in the county of Rensselaer and State of New York, have invented and produced a new and original Design for a Horseshoe, of which the following is a specification, reference being had to the accompanying drawings, forming part thereof.

5 Figure 1 is a plan of the upper or hoof-bearing surface of a blank horseshoe having my said design; Fig. 2, an elevation of a section of the same, taken at the line $z z$ in Figs. 1, 3, and 4 and viewed in the direction pointed 10 by the arrows y ; Fig. 3, an elevation of a section of the same horseshoe, taken at the line $x x$ in Figs. 1 and 2 and seen in the direction indicated by the arrow w ; and Fig. 4, an elevation of a section of the same at the said 15 line $x x$ and viewed in the direction of the arrow v .

10 Figure 1 is a plan of the upper or hoof-bearing surface of a blank horseshoe having my said design; Fig. 2, an elevation of a section of the same, taken at the line $z z$ in Figs. 1, 3, and 4 and viewed in the direction pointed 15 by the arrows y ; Fig. 3, an elevation of a section of the same horseshoe, taken at the line $x x$ in Figs. 1 and 2 and seen in the direction indicated by the arrow w ; and Fig. 4, an elevation of a section of the same at the said 20 line $x x$ and viewed in the direction of the arrow v .

The distinguishing feature of my design for horseshoes consists of two projections, as 25 A A, opposite to each other, just forward of the two heel portions of the shoe and extend-

ing inward in tapering form toward each other, essentially as shown in Fig. 1, the upper surfaces, $b b$, of said projections being in about the same plane with the main upper surface, c , of the continuous bent portion forward of said two projections, substantially as indicated by the aforesaid drawings.

What I claim is—

The design for a horseshoe herein shown and described, the same comprising the two 35 projections A A, opposite to each other, just forward of the two heel portions and extending inward in tapering form toward each other, with the upper surfaces of said projections and the upper surface of the continuous 40 bent portion forward of said projections in about the same plane, as set forth.

In testimony whereof I hereunto set my hand, in the presence of two subscribing witnesses, this 30th day of January, 1889.

HENRY J. GOLDMAN.

Witnesses:

FRANCIS A. SIMS,
THOMAS S. BRESLIN.
